UNITED STATES PATENT OFFICE.

ALBERT JAEGERS, OF SUFFERN, NEW YORK.

DESIGN FOR A MEMORIAL ARTICLE.

52,797.

Specification for Design.

Patented Dec. 24, 1918.

Application filed October 1, 1918. Serial No. 256,476. Term of patent 7 years.

To all whom it may concern:

Be it known that I, ALBERT JAEGERS, a citizen of the United States of America, residing at Suffern, county of Rockland, State of New York, have invented a new, original, and ornamental Design for a Memorial Article, of which the following is a specification, reference being had to the accompanying drawing, forming part thereof.

The figure of drawing is a plan view of a plaque showing my new design.

I do not claim the plaque as a part of the design as the same is applicable to me-

dallions, gravestones and other structures of a memorial character, designed to commemorate individual or personal losses by death on the battlefield.

The elements of the design as shown include the representation of a head superposed on a service star which seems to rest on a mass of flowers, surrounded by a suitable inscription.

I claim:

The ornamental design for a memorial article substantially as shown and described.

ALBERT JAEGERS.
